corporation of Pennsylvania

Application August 9, 1944, Serial No. 114,798

Term of patent 14 years

(Cl. D81—4)

To all whom it may concern:

Be it known that I, Arthur T. Thygeson, a citizen of the United States, residing at Larchmont, in the county of Westchester and State of New York, have invented a new, original, and ornamental Design for a Combination Solid and Fluid Fuel Range, of which the following is a specification, reference being made to the accompanying drawing, forming a part thereof.

Figure 1 is a perspective view of a combination solid and fluid fuel range, showing my new design.

Figure 2 is an end elevation viewed from the opposite end to that seen in Figure 1.

I claim:

The ornamental design for a combination solid and fluid fuel range, as shown.

ARTHUR T. THYGESEN.
